UNITED STATES PATENT OFFICE.

ALDEN L. PUTNAM, OF DETROIT, MICHIGAN, ASSIGNOR, BY MESNE ASSIGNMENTS, TO DETROIT PRESSED STEEL COMPANY, OF WILMINGTON, DELAWARE, A CORPORATION OF DELAWARE.

VEHICLE-WHEEL.

1,380,925.

Specification of Letters Patent. Patented June 7, 1921.

Application filed March 27, 1919. Serial No. 285,499.

To all whom it may concern:

Be it known that I, ALDEN L. PUTNAM, a citizen of the United States of America, residing at Detroit, in the county of Wayne 5 and State of Michigan, have invented certain new and useful Improvements in Vehicle-Wheels, of which the following is a specification, reference being had therein to the accompanying drawings.

10 The invention relates to vehicle wheels of the dished disk type, and the invention consists in the construction of reinforcing means for the disk as hereinafter set forth.

In the drawings:

15 Figure 1 is a cross-section of the wheel through an axial plane thereof;

Fig. 2 is a side elevation;

Fig. 3 is a view similar to Fig. 1 showing the reversed wheel.

20 In the present state of the art certain constructions of wheel of the above type have the dished disk arranged to cross the central plane or plane of impact. This adds strength and resiliency to the wheel, but as

25 usually constructed the wheel cannot be reversed without altering the location of the tread. Again, it is usual to form such disks of a section tapering from the center toward the periphery so as to combine

30 strength with lightness. With my improved construction the advantage of a dish crossing the central plane is retained in a construction which is reversible; and a further feature is the securing of strength and

35 lightness in a construction dispensing with the tapering cross-section and which may be pressed from uniform gage metal.

As shown, A is the hub which is provided 40 with an outwardly-extending flange B to which the dished disk C is secured. This disk is secured at its peripheral edge to a flange D on the rim E on one side of the central plane or plane of impact of the wheel, while the central portion of the disk

45 crosses the plane of impact and is upon the opposite side thereof. Thus to secure the disk in proper position upon the hub the flange B is arranged at one side of the central plane of impact or adjacent to the central portion of the disk.

50 It is usual to secure the necessary strength in the disk by making the central portion, which is secured to the flange of the hub, of heavy gage and tapering the section from

this point toward the periphery. Instead 55 of following this construction in the present invention, the disk may be formed of uniform gage metal and the central portion thereof strengthened by a reinforcement F. Furthermore, this reinforcement is preferably oppositely dished so that its inner portion is arranged upon the opposite side of the central plane of impact from the corresponding portion of the disk proper, while the outer edge of the reinforcement is 60 riveted or otherwise secured to the disk intermediate the center and the periphery. This construction has the twofold advantage of making the wheel symmetrical so that it may be reversed without change in 65 position of the tread and also of reinforcing the construction where uniform gage metal is used instead of a tapering cross-section.

The disk is secured to the hub by suitable clamping bolts or studs G passing 75 through alined apertures in the main portion and reinforcement of the disk and engaging the flange B. There are also provided a series of driving pins H secured to and extending laterally from the flange B 80 intermediate the clamping bolts and engaging alined apertures in the disk and reinforcement. I is a spacer or strut arranged between the disk and the member F; this being preferably an annular member of 85 channel cross-section, the sides of the channel being respectively inside and outside of the bolts G and pins H.

Where the reversible feature of the construction is dispensed with, the clamping 90 bolts may be permanently attached to the disk with provision for successively operating the same in clamping or detaching the disk from the hub. As shown in Fig. 1, the bolts G have an unthreaded shank portion 95 passing through the disk and the spacer I and a threaded portion engaging a threaded bearing J in the flange of the wheel. As shown, these threaded bearings are formed of separate nut members having heads J' seated in recesses in the rear face of the flange B and sleeve portions J² extending through apertures in said flange and projecting forward therefrom to engage corresponding apertures in the member F. The bolt G has a collar K preferably formed by an interiorly threaded ring screwed upon the threaded portion of the 100

bolt, and this collar serves as a stop for limiting the outward movement of the bolt and therefore retaining it in engagement with the disk. At the same time the amount 5 of free movement of the collar between the disk and reinforcing member F is sufficient to permit of screwing each bolt into or out of its corresponding nut J without movement of the disk or of the other bolts attached thereto.

What I claim as my invention is:

1. In a vehicle wheel, the combination with a rim and hub, of a main dished disk extending between said rim and hub, an oppositely 15 dished reinforcing disk spaced from the first mentioned disk at the hub and secured to the main disk at a point remote from the rim thereof, a spacer between said disks having concentric inner and outer portions, and 20 means for securing the disk to the hub passing through apertures in said disks intermediate the concentric portions of said spacer.

2. In a vehicle wheel, the combination with 25 a rim, a hub and a flange extending outward from said hub, of a dished disk extending between said hub and rim, an oppositely dished reinforcing disk having its peripheral edge secured to the main disk intermediate the 30 hub and the rim, a spacer between said disks, a securing member for said disks passing through alined apertures therein and having a threaded engagement with the flange on said hub, and a retainer on said securing 35 member in the space between said disks permitting longitudinal movement of the fastener in screwing and unscrewing the same independent of the movement of the disk.

3. In a vehicle wheel, the combination 40 with a rim and a hub having an outwardly extending flange, of a dished disk extending between said hub and rim, an oppositely

dished reinforcing disk having its peripheral edge attached to the main disk at a point intermediate the rim and hub and its inner 45 edge being spaced from the main disk, a fastener passing through alined apertures in said disk and having a threaded portion for engaging a correspondingly threaded portion of the hub flange, and a collar on said fastener between the disks forming a retainer for holding said fastener from disengagement and permitting freedom of longitudinal adjustment while screwing and unscrewing the same from said flange. 50

4. In a vehicle wheel, the combination with a hub and rim and dished disk extending therebetween, of an oppositely dished reinforcing disk, peripherally secured to the main disk and engaging the hub in spaced relation to the main disk, and means engaging the two said disks and securing the same to the hub, having a retaining portion intermediate the disks. 60

5. In a vehicle wheel, the combination 65 with the hub and rim thereof of a disk extending between said hub and rim and crossing the plane of impact and dished substantially throughout its entire area, and an oppositely dished reinforcing disk peripherally secured to the main disk, substantially 70 in the plane of impact and having a bearing on the hub spaced from that of the main disk.

6. In a vehicle wheel, a combination with 75 the hub and rim and a disk extending therebetween and dished substantially throughout its entire area of an oppositely dished reinforcing disk peripherally secured to the main disk at a point remote from the rim, 80 and having a bearing on the hub spaced from that of the main disk.

In testimony whereof I affix my signature.
ALDEN L. PUTNAM.
